CLAIM

I claim the ornamental design for a container lid, as shown and described.

DESCRIPTION

FIG. 1 is a right side view a container lid according to the invention;

FIG. 2 is a left side view thereof;

FIG. 3 is a front view thereof;

FIG. 4 is a rear view thereof;

FIG. 5 is a top view thereof;

FIG. 6 is a bottom view thereof;

FIG. 7 is a cross sectional view taken at line 7-7 of FIG. 1; and,

FIG. 8 is a partial cross sectional view taken from FIG. 7. The broken lines in the figures form no part of the claimed design. The dot-dash lines represent the designation of an enlargement view and form no part of the claim.
